WATER TUBE STEAM GENERATOR

Hans C. Egloff, Bern, Switzerland, assignor to
the firm of Sulzer Frères Société Anonyme,
Winterthur, Switzerland

Application January 28, 1932, Serial No. 589,402,
and in Switzerland February 7, 1931

7 Claims. (Cl. 122—451.1)

This invention relates to water tube steam generators of the high pressure type in which the working medium is conveyed through a system of evaporating tubes connected in parallel.

5 According to the present invention not only the main supply of working medium to the inlet end of the tube system but also additional supplies introduced at intermediate points in the several tubes are regulated in accordance with the temperature of the steam generated. Conveniently 10 the regulation is effected in accordance with the temperature of the steam generated in the individual tubes.

15 Two constructions of water tube steam generator according to the present invention are illustrated diagrammatically and by way of example in Figures 1 and 2 respectively of the accompanying drawings.

20 In the construction illustrated in Figure 1 the steam generator includes a set of preliminary heating tubes 1a, 1b, 1c connected in parallel and to a main feed pipe through which liquid medium is fed by a pump 2, the preliminary heating tubes having a common delivery pipe 3. A second set 25 of tubes 4a, 4b, 4c, 4d are connected in parallel and to the pipe 3, these tubes delivering superheated steam to a common steam supply pipe 5 which leads to the point or points of consumption. The tubes 1a, 1b, 1c and 4a, 4b, 4c, 4d are supplied 30 with heat by any suitable means.

A series of temperature-controlled devices 6a, 35 6b, 6c, 6d, each associated with one of the tubes 4a, 4b, 4c and 4d, control additional supplies of working medium introduced from the main feed pipe through pipes 7a, 7b, 7c, 7d so that this additional medium is fed to each tube at a point 40 therein where the medium is already in the evaporated state. Each of the devices 6a, 6b, 6c, 6d is connected by a pipe 8 to a servomotor 9 adapted to control a throttling device or valve 10 disposed in the pipe through which additional medium is fed to the corresponding tube. In addition, each of the temperature-controlled devices 45 6a, 6b, 6c, 6d is connected by a pipe 11 to a servomotor 12 which is adapted to control a throttling device or valve 13 disposed in the main feed pipe.

When the temperature of the superheated steam generated rises above a predetermined 50 value the temperature-controlled devices 6a, 6b, 6c, 6d actuate the valves 10 so as to increase the quantity of additional medium fed through the pipes 7a, 7b, 7c, 7d, whereby the temperature of the generated steam is reduced and, since the quantity of additional medium supplied to each 55 of the tubes 4a, 4b, 4c, 4d is individually con-

trolled by the temperature-controlled device associated with that tube, the temperature of the steam delivered will be substantially the same for each of the tubes 4a, 4b, 4c, 4d. If, however, the temperature of the steam delivered by the tubes 4a, 4b, 4c, 4d is still above the desired maximum when the limits of regulation by means of the valves 10 have been reached the temperature-controlled devices 6a, 6b, 6c, 6d will transmit an impulse to the servomotor 12 and thereby adjust 60 the valve 13 so as to increase the quantity of medium introduced to the first set of tubes 1a, 1b, 1c, the temperature of the steam generated by the tubes 4a, 4b, 4c, 4d being thus reduced until the control devices 6a, 6b, 6c, 6d and valves 10 70 and 13 are returned to their normal positions.

When the temperature of the superheated steam generated by the tubes 4a, 4b, 4c, 4d drops below a predetermined value the temperature-controlled devices 6a, 6b, 6c, 6d will actuate the 75 valves 10 so as to decrease the quantity of additional medium introduced through the pipes 7a, 7b, 7c, 7d until the temperature of the generated steam is again restored to the desired value. If, however, the temperature of the generated steam 80 is still below that desired when the limits of operation of the valves 10 have been reached the control devices 6a, 6b, 6c, 6d will transmit an impulse to the servomotor 12 so as to adjust the valve 13 and thereby reduce the quantity of medium introduced to the first set of tubes 1a, 1b, 1c 85 until the temperature of the generated steam has been restored to the desired value and the devices 6a, 6b, 6c, 6d and valves 10 are returned 90 to their normal positions.

In the construction illustrated in Figure 2 a temperature-controlled device 14 influenced in accordance with the temperature of the medium delivered to the pipe 3 by the preliminary heating tubes 1a, 1b, 1c is adapted to control the delivery 95 of a main feed pump 2 which supplies liquid medium to the inlet end of the system. Additional working medium is introduced to each of the individual tubes 4a, 4b, 4c, 4d by means of a pumping device 16, each of these pumping devices being in turn independently supplied with medium through the pipes 7a, 7b, 7c, 7d. In this construction each of the temperature-controlled devices 6a, 6b, 6c, 6d is adapted to control the delivery of the pumping device 16 associated with the corresponding tube so that when the temperature of the steam generated by the tubes 4a, 4b, 4c, 4d rises above the desired value 105 the temperature-controlled devices 6a, 6b, 6c, 6d regulate the delivery of the pumping devices 16 110

so as to increase the quantity of additional medium introduced to each of the tubes. Similarly when the temperature of the steam generated by the tubes 4a, 4b, 4c, 4d drops below the desired 5 value, the deliveries of the pumping devices 16 are reduced so that the temperature of the generated steam is restored.

In order to supplement the effect of the additional feeding by means of the devices 16, a 10 means 14 for recording the temperature is provided between the tube system 1a-1c and the pipe system 4a-4d, which exerts an impulse through the conduit 15 on the main feed pump 2, so that the feeding quantity is regulated in 15 dependence on the temperature of the working medium flowing from the tube system 1a-1c to the tube system 4a-4d. In this case the regulation can be effected in a manner such that when 20 things settle down, the regulating devices 6a-6d and the feeding devices 16 are returned to the normal central position and the change in load is only received by the main feed pump.

It will be understood that the constructions above described are given by way of example 25 only and that details may be modified without departing from the invention. For example, the control devices for regulating the main feed and additional supplies of working medium may be constructed and operated as desired, and when 30 pumping devices are employed for supplying the working medium each pumping device may be regulated by varying its speed or stroke. Alternatively, the quantity of working medium may be regulated by varying the effective cross-section 35 of the inlet of the suction or delivery pipe of the pumping device which supplies it. Further, the main supply of medium introduced to the inlet end of the system may be effected by several pumping devices in which case only one of such 40 pumping devices may if desired be regulated.

What I claim is:

1. In a water tube steam generator of the type set forth, in combination a plurality of preliminary heating tubes arranged in parallel and connected on the one hand to a main feed pipe and on the other hand to a common delivery pipe, a set of secondary heating tubes arranged in parallel and connected to said common delivery pipe, means for supplying additional working medium to each of said secondary heating tubes, devices associated with said secondary heating tubes by means of which devices the quantity of additional medium supplied to said secondary heating tubes is regulated in accordance with the temperature 45 of the steam generated in them, and means for regulating the main supply of working medium fed to said preliminary heating tubes in accordance with the temperature of the steam generated in said secondary heating tubes, so that not only the main supply of working medium to the inlet end of the system but also additional supplies introduced at intermediate points in the several tubes of said secondary heating tubes are regulated in accordance with the temperature 50 of the steam generated.

2. In a water tube steam generator of the type set forth, in combination a plurality of preliminary heating tubes arranged in parallel and connected on the one hand to a main feed pipe and on the other hand to a common delivery pipe, a set of secondary heating tubes arranged in parallel and connected to said common delivery pipe, means for supplying additional working medium to each of said secondary heating tubes, devices associated with said secondary heating 55

tubes by means of which devices the quantity of additional medium supplied to said secondary heating tubes is regulated in accordance with the temperature of the steam generated in them, and means for regulating the main supply of working medium fed to said preliminary heating tubes in accordance with the temperature of the steam generated in said preliminary heating tubes.

3. In a water tube steam generator as set forth 60 in claim 1, the combination of said two sets of heating tubes with temperature-controlled devices respectively associated with said secondary heating tubes and adapted in accordance with the temperature of the steam generated in said secondary heating tubes to regulate not only the additional supply of medium fed to each of said secondary tubes but also the main supply of working medium fed to said preliminary heating tubes, the regulation of the main feed supply 65 being effected after the limit of regulation of the additional supply has been reached.

4. In a water tube steam generator as set forth 70 in claim 2, the combination of said two sets of heating tubes with temperature-controlled devices respectively associated with the several tubes of said secondary heating tubes and adapted to regulate the supplies of additional medium fed to said secondary heating tubes in accordance 75 with the temperature of the steam generated in said secondary heating tubes, and a temperature-controlled device adapted to regulate the main supply of medium to said preliminary heating tubes in accordance with the temperature of the steam generated in said preliminary heating tubes.

5. In a water tube steam generator of the type set forth, in combination a plurality of preliminary heating tubes arranged in parallel and connected on the one hand to a main feed pipe and on the other hand to a common delivery pipe, a throttling device in said main feed pipe, a set of secondary heating tubes arranged in parallel and connected to said common delivery pipe, a pipe branching from said main feed pipe in front of said throttling device, delivery pipes leading from said branch pipe to each of said secondary heating tubes for supplying additional working medium to each of said secondary heating tubes, a temperature-controlled device associated with each of said secondary heating tubes, a servomotor arranged in a pipe leading from each of said temperature-controlled devices to said delivery pipes, a throttling device in each of said delivery pipes, pipes connecting said servomotors to said throttling devices and branch pipes leading from said temperature-controlled devices to a common servomotor connected to said throttling device in said main feed pipe, so that the main supply of working medium to the inlet end of the system as well as the additional supplies introduced at intermediate points in the several tubes of said secondary heating tubes are regulated in accordance with the temperature of the steam generated.

6. In a water tube steam generator of the type set forth, in combination a plurality of preliminary heating tubes arranged in parallel and connected on the one hand to a main feed pipe and on the other hand to a common delivery pipe, a throttling device in said main feed pipe, a set of secondary heating tubes arranged in parallel and connected to said common delivery pipe, a pipe branching from said main feed pipe ahead of said throttling device, delivery pipes leading from 145

said branch pipe to each of said secondary heating tubes for supplying additional working medium to each of said secondary heating tubes, a temperature-controlled device associated with 5 each of said secondary heating tubes, a servomotor arranged in a pipe leading from each of said temperature-controlled devices to said delivery pipes, a throttling device in each of said delivery pipes, pipes connecting said servomotors 10 to said throttling devices and branch pipes leading from said temperature-controlled devices to a common servomotor connected to said throttling device in said main feed pipe, so that the main supply of working medium to the inlet end 15 of the system as well as the additional supplies introduced at intermediate points in the several tubes of said secondary heating tubes are regulated in accordance with the temperature of the steam generated.

20 7. In a water tube steam generator of the type

set forth, in combination a plurality of preliminary heating tubes arranged in parallel and connected on the one hand to a main feed pipe and on the other hand to a common delivery pipe, a temperature-controlled device in said common delivery pipe connected to a pump feeding said main feed pipe, a set of secondary heating tubes arranged in parallel and connected to said common delivery pipe, a pump connected to each of said secondary heating tubes adapted to supply additional working medium to each of said secondary heating tubes, a temperature-controlled device associated with each of said secondary heating tubes and pipes connecting said temperature-controlled devices to said pumps feeding said secondary heating tubes, said temperature-controlled device in said common delivery pipe being arranged in front of said secondary heating tubes connected to said common delivery pipe.
